Primary Examiner — Prabhakar Deshmukh(74) *Attorney, Agent, or Firm* — NSIP Law(57) **CLAIM**

The ornamental design for an audio player, as shown and described.

DESCRIPTION

FIG. 1 is a perspective view of an audio player showing my new design;

FIG. 2 is a front elevation thereof;

FIG. 3 is a rear elevation thereof;

FIG. 4 is a left side elevation thereof;

FIG. 5 is a right side elevation thereof;

FIG. 6 is a top plan view thereof;

FIG. 7 is a bottom plan view thereof;

FIG. 8 is a left side elevation thereof, shown in environmental use;

FIG. 9 is a rear perspective view thereof;

FIG. 10 is a bottom perspective view thereof;

FIG. 11 is a front elevation thereof, shown in environmental use;

FIG. 12 is a rear elevation thereof, shown in another environmental use; and,

FIG. 13 is a top plan view thereof, shown in another environmental use.

The broken lines in FIGS. 8, 11, 12, and 13 indicate environment and form no part of the claimed design. Other broken lines throughout the drawing indicate unclaimed portions and form no part of the claimed design.
